US00D594009S

(12) **United States Design Patent**
Nakano et al.

(10) **Patent No.:** US D594,009 S
(45) **Date of Patent:** ** Jun. 9, 2009

(54) **PERSONAL COMPUTER**

(75) Inventors: **Tomomi Nakano**, Tokyo (JP); **Hirotoshi Muraki**, Shizuoka (JP); **Shiyuichi Sugiyama**, Shizuoka (JP); **Kazuhiko Aoyama**, Shizuoka (JP); **Naoki Katou**, Tokyo (JP)

(73) Assignees: **NEC Corporation**, Tokyo (JP); **NEC Access Technica, Ltd.**, Shizuoka (JP)

(**) Term: **14 Years**

(21) Appl. No.: **29/325,750**

(22) Filed: **Oct. 6, 2008**

(30) **Foreign Application Priority Data**

Apr. 9, 2008 (JP) 2008-009088

(51) LOC (9) Cl. **14-02**

(52) U.S. Cl. **D14/439**; D14/315

(58) **Field of Classification Search** D14/315-327, D14/348, 349, 351, 353-355, 385, 388-398, D14/432-434, 439-447; 361/679.01, 679.02, 361/679.07, 679.08, 679.09, 679.1, 679.18, 361/679.19, 679.2, 679.26, 679.27, 679.28, 361/679.31, 679.55, 679.57, 679.58
